SIGNAL TRANSLATING DEVICE

Henry H. Bruderlin, Hermosa Beach, Calif.

Application June 21, 1941, Serial No. 399,221

6 Claims. (Cl. 179—100.41)

This invention relates to signal translating devices, and more particularly to an improved device for quality recording or reproducing of sound by the aid of a vibratory stylus.

In recording or reproducing sound on a record member, a stylus is placed in contact with a record groove. In recording, the stylus is vibrated to cause the recording point of the stylus to vibrate laterally or vertically, to form a lateral or a hill-and-dale record, respectively. The stylus point may actually cut the record, or may operate as a pressure embossing tool. Vibrations may be imparted to the stylus electromagnetically, the signaling impulses determining the amplitude and frequency of the vibrations. Conversely, in reproducing such a record, a stylus is vibrated by the undulations in the record. The vibrations thus produced are caused to induce corresponding signaling impulses in a circuit governing sound reproduction by a loud speaker.

In either case, the mounting of the stylus is quite important. It is essential that the stylus follow the impulses as accurately as possible, without introducing undesired extraneous vibrations. Ordinarily a resilient restraint is placed upon the stylus, tending to return the stylus to a neutral or inactive position, to ensure that the forces influencing the stylus are suitably rendered effective to vibrate the stylus in substantially accurate conformity with these forces. Restraints of this general character, such as a resilient rubber mounting, or a spring mounting, or a combination of the two, have been heretofore proposed and used. However, it is difficult by means usually employed to secure the highly desirable cooperative restraint without the introduction of disturbing damping or resonant effects.

It is one of the objects of this invention to improve the mounting of such a stylus and to minimize these disturbing characteristics.

It is another object of this invention to provide a stylus mounting that is simple and inexpensive to construct, and one that produces a natural frequency of the vibratory system that is substantially ineffective in interfering with the accuracy of the recording or reproduction.

It is still another object of this invention to provide a mounting that is protected against injury even upon rough usage, such as dropping of the head incorporating the stylus mount.

The stylus mounting is furthermore so arranged that only a light spring pressure may be utilized to hold the stylus point in operative position against the record groove; thereby reducing

groove wear, as well as stylus wear. This feature, coupled with the inherently small inertia of the vibratory system, ensures that even very low amplitude signals may be accurately recorded or reproduced, resulting in a very sensitive unit.

It is a further object of this invention to make it possible to limit the maximum pressure that may be applied upon the record groove, resulting in the assurance against detrimental scratching even when the head is forcibly moved transversely of the record grooves.

In accordance with the present invention, the vibratory part of the recorder or the reproducer can be constructed of extremely small mass. Its moment of inertia may be thus reduced to a value of the order of one one-hundredth of that of the conventional pick-ups or recorders. In the relatively massive conventional reproducing devices, the inertia of the moving parts resulted in rapid wear, due to the accelerating reactions between the groove and the stylus. Also, in the prior art devices, due to their weight and shape, the moving mass was capable of internal resonant vibration in several modes and at several frequencies which strongly and adversely affected their frequency characteristics. These effects caused additional record wear at those frequencies.

It is accordingly still a further object of the present invention to provide an extremely small vibratory armature which is incapable of internal resonance at any frequency in the useful range; and to mount the armature in such manner that the assembly of the armature and its mounting as installed in the pick-up or recorder will ordinarily have only one possible type of extraneous resonant vibration, which is outside of or above the useful frequency range.

These and further objects of the invention will become apparent in the following description of preferred embodiments thereof illustrated in the drawings, in which:

Fig. 1 is a vertical longitudinal sectional view of the invention.

Figs. 2 and 3 are transverse sectional views taken respectively along lines 2—2 and 3—3 of Fig. 1.

Fig. 4 is a bottom plan view, partly broken away, of the device shown in Fig. 1.

Fig. 5 is a pictorial view of some of the parts of the device shown in Fig. 1, illustrated in separated form.

Fig. 6 is an enlarged fragmentary sectional view of the device, shown in use in connection with a record.

Fig. 7 is an enlarged fragmentary end view of the device.

Fig. 8 is a side view partly in section, of a modified form of the device.

Fig. 9 is an end view corresponding to Fig. 8.

Fig. 10 is a transverse sectional view taken along line 10—10 of Fig. 8.

Fig. 11 is a bottom plan view of the device shown in Fig. 8.

Fig. 12 is a greatly enlarged view in perspective, illustrating a modified form of parts of the invention.

Fig. 13 is a cross-sectional view taken along line 13—13 of Fig. 12.

Fig. 14 is a view corresponding to Fig. 12, of a further modified form of parts of the invention.

Fig. 15 is a cross-sectional view taken along line 15—15 of Fig. 14.

Fig. 16 is a view corresponding to Fig. 12 of a still further modified form of parts of the invention.

Fig. 17 illustrates the mode of operation of the device illustrated in Fig. 16.

The device illustrated in Figs. 1 to 7 inclusive may be used either for recording or for reproducing sound in conjunction with a usual record. Record 1 may be of disk form with a series of record grooves on its surface. Cooperating with the grooves is stylus point 2. The illustrated record grooves correspond to lateral recording, as distinguished from a hill-and-dale record. The stylus point 2 of the device of Figs. 1 to 7 is, for either the recording or reproducing of sound intended to vibrate in a direction transverse to the record grooves, rather than in a vertical direction along the depth of the groove as in the hill-and-dale system. The stylus point 2, however, is supported so as to be flexible in the vertical direction. It is to be understood that tape-type or other record forms may be used in place of the usual disk record. Also, it is to be understood that by suitable variation in the supporting structure for the stylus, the device of the invention may be readily converted for hill-and-dale recording and reproducing.

Stylus point 2 may be made integral with a stylus body 3, or may otherwise be firmly attached thereto, the stylus body 3 and point 2 forming a stylus structure. The stylus is shown supported upon a member 4 capable of vibration in a manner to be hereinafter described. For reproducing purposes, the vibrations are transmitted to stylus 3 by the action of the lateral record in the record grooves upon stylus point 2. For recording purposes the vibrations are transmitted electromagnetically to the stylus 3 in accordance with the sound impulses to be recorded, whereupon the stylus point 2 cuts or embosses the surface of record 1 in conformity with the impulses. Since the function of recording as distinguished from reproduction in general corresponds to a reversal of forces operating upon the member 4, the following description of the invention device will be in connection with its use as a reproducer. Operation of the device as a recorder will be defined hereinafter.

Member 4 is made of magnetic material so that it may operate as an armature in an air gap 5 between pole pieces 6 and 7. Assuming that the structure comprising the point 2, stylus body 3 and the armature 4 can swing about a point 8 (Fig. 7) spaced from the polar axis 9, it is seen that movement of the stylus in a clockwise direction due to the conformation of the lateral record, will reduce the magnetic reluctance between the

armature 4 and pole piece 7, simultaneously increasing the magnetic reluctance between armature 4 and pole piece 6. Conversely, a vibration of the stylus in a clockwise direction about point 8 will increase the magnetic reluctance between the armature 4 and the pole piece 7, simultaneously reducing the magnetic reluctance between armature 4 and the pole piece 6. Accordingly, the vibrations of the armature 4 imparted by the lateral record 1 are effective in altering the reluctances of magnetic paths.

These variations in the magnetic path reluctances vary the lines of force passing through the core of pick-up coil 10, inducing an electromotive force therein. The magnetic circuit for coil 10 will be described in detail hereinafter. Coil 10 is provided with leads 11 and 12 which may be connected to an appropriate amplifier and loud speaker system, or other suitable sound reproducer.

Coil 10 is shown disposed over a core 13, illustrated as made up of a series of laminations. Core 13 is shown with its left hand surface in contact with a permanent magnet 14, having its polar faces 21 and 22 in contact with the extensions 15 and 16 of pole pieces 6 and 7. Accordingly, if pole piece 6 forms a north pole, then pole piece 7 forms a corresponding south pole, as indicated in Figs. 2 and 7. A magnetic member 17 is provided for completing the magnetic circuit through armature 4. Magnetic member 17 abuts the lower surface of the leg 18 of the core 13. Member 17 extends toward the left to form a face 19 cooperating with the rear surface 20 of the armature 4. Surfaces 19 and 20 approach quite closely together.

Assuming that the armature 4 is in its neutral or central position, the resultant flux in core 13 is neutralized. This is apparent when it is realized that core 13 abuts the central or neutral zone of magnet 14. Magnet 14 may be assumed as being made up of two magnets, abutting at the region where the core contacts it; this being indicated by dot-and-dash line 100 of Fig. 2. Flux from the north end corresponding to face 21 can flow through extension 15, armature 4, member 17, and through core 13 toward the left as viewed in Fig. 1. This flux passes back to the region adjacent line 100, corresponding to a south pole of this half of magnet 14. Similarly, flux from the north end of the right hand portion of magnet 14, corresponding to the region adjacent line 100, flows through core 13 in the direction such as to neutralize the flux in core 13 that is set up by the left hand half of magnet 14 as viewed in Fig. 2.

Assuming now that the magnetic reluctance from armature 4 to the south pole 7 is reduced by movement of the armature 4 in a counter-clockwise direction as illustrated in Fig. 7, then flux may pass through the core 13 in a magnetic circuit including pole 7. This circuit includes the south polar region of the left hand half of magnet 14, adjacent line 100 (Fig. 2), through core 13 in the direction of arrow 23 in Fig. 1, member 17, armature 4, polar extension 7, back to the south pole of magnet 14. A magnetic flux through this path will accordingly pass through core 13 in the direction of arrow 23. The flux set up in this direction is quite strong, because the reluctance of the circuit is reduced by the approach of armature 4 toward polar projection 7.

Another magnetic circuit of greater reluctance is simultaneously effective through which mag-

netic flux may pass. This magnetic flux is opposed to the magnetic flux whose direction is represented by the arrow 23, but of less intensity, due to the greater reluctance of the opposed flux path. The resultant magnetic flux is therefore in the direction of arrow 23. The weaker flux path may be traced as follows: from the north polar end of the left hand half of magnet 14 (Fig. 2), pole piece 6, armature 4, member 17, leg 18, core 13, back to the north polar region corresponding to line 100.

As armature 4 is vibrated about axis 8, the direction of the flux through the core 13 passes through successive reversals. This is due to the fact that armature 4 alternatively approaches pole pieces 7 and 6, setting up resultant opposite variations in magnetic reluctance between the armature and these pole pieces. These changes of flux through core 13 induce an electromotive force in coil 10. The amplitude and frequency of this electromotive force are in conformity with the record grooves.

The manner in which armature 4 is supported for vibratory movement of this character will now be described. There is provided a flat spring member 24, preferably made of non-magnetic spring metal, such as phosphor bronze or spring brass. The upper surface of armature 4 is attached to the free end of spring 24, as by soldering or the like. The opposite end of spring 24 is clamped between a non-magnetic supporting member 25 and magnetic member 17 or is preferably attached to member 17 as by soldering. A flat head screw 26 passes through member 17, and is threaded into member 25. This single screw mounting allows the armature-spring assembly to be quickly replaced when necessary.

The configuration of member 25 is shown most clearly in Fig. 5. It is provided with downwardly extending ears or lugs 27 on opposite sides of its rear end, between which the rear end of member 17 is disposed. Member 25 is also provided with a rear slot 28 within which the lower end of leg 18 is accommodated. It is also provided with a front slot 29 contiguous with arms 30 and 31 between which armature 4 may extend. Lugs 27 serve to center member 17. Therefore in conjunction with screw 26, armature 4 is constrained to be accurately positioned in the gap between the pole pieces 6 and 7. These pieces may be soldered to arms 30 and 31. Alternatively member 25 may be eliminated and its functions accomplished by a plastic member of similar or of different shape. In some constructions, spring 24 may be made of magnetic material, obviating the necessity of using member 17.

To provide a suitable casing for the entire head, a rear supporting member 32 made of insulation material may be provided. Support 32 in conjunction with a coacting housing 33, encloses the device except for a comparatively narrow slot 34 in the bottom wall of the casing. Armature 4 may extend through slot 34. Permanent magnet 14 may be disposed on an inwardly turned lip 35 formed in the left hand wall of casing 33. Fastening screws 36, (Figs. 1 and 4), may be provided for holding the housing 33 in position with respect to the member 32. Furthermore, in order to hold core 13 securely against magnet 14, use may be made of a leaf spring 37 acting on the rear end of the core 13 and anchored, as with a rivet 38, to member 32.

An important feature of this construction is the character of spring 24 supporting armature 4. The support provided is such as to permit arma-

ture 4 to vibrate in the air gap between pole pieces 6 and 7 by twisting of spring 24 about its longitudinal axis. Spring 24 may be aptly termed a torsional spring. It is about the longitudinal axis of spring 24 that the lateral vibrations of the stylus occur. Furthermore, spring 24 is capable of being flexed in a vertical direction. The operating pressure on the stylus is sufficient to cause the flexure of spring 24 upwards to the position indicated in Fig. 7. This pressure may be as low as one-half ounce, with attendant satisfactory operation. This is only a fraction of pressure ordinarily utilized on conventional magnetic pick-up units, which generally require approximately three ounces of pressure. Armature 4 is purposely made rather deep, so that even upon the flexure of spring 24 the armature extends fully across the magnetic field between pole pieces 6 and 7. Furthermore, the free end of spring 24 ordinarily, but not necessarily, serves as the sole support for the armature.

Spring 24 may aptly be referred to as a cantilever leaf spring. It has three degrees of deflection; one in torsion about its longitudinal axis; one in flexure in a direction perpendicular to the plane of the spring; and one in flexure in the plane of the spring. The torsional stiffness of spring 24 must be sufficient to prevent the armature 4 from sticking to the poles if it is displaced that far, but not stiff enough to prevent the stylus from freely following the vibrations in the record. The vertical flexure stiffness of the spring must be sufficient so that with the proper operating pressure applied to the stylus the spring will not deflect excessively. The spring must be sufficiently flexible in the vertical direction so that if excessive pressure is applied to the stylus it will recede between the pole pieces due to deflection of the spring so that neither the stylus or other parts will be injured because of excessive stylus pressure.

The lateral stiffness of spring 24 must be sufficient so that under operating conditions, that is, with the stylus applied to the record, the lateral resonant frequency of the vibratory system comprising the armature and spring will be above the useful operating range of the pick-up. This is the only type of extraneous vibration which will occur in the operating mechanism of this pick-up. The torsion axis of spring 24 is transverse to the polar axis 8, but spaced a considerable distance above it. In this way the amplitude of movement of armature 4 between pole pieces 6 and 7 is nearly the same as the vibratory movement of the tip 2.

The entire vibrating system of the invention device is extremely light. The natural resonant frequency of the supporting system may accordingly be readily designed to lie beyond the useful audio frequency range of reproduction. Extraneous or disturbing oscillations are therefore largely avoided or suppressed. The resonant frequency of the combined stylus 2, 2, armature 4 and spring suspension 24 may in practice be constructed to lie between 6000 cycles per second to 10,000 cycles per second, or even higher. Thus, the natural tendency of the overall frequency characteristics in reproduction by records to taper off may be directly compensated at the higher frequency end by this resonant characteristic. In other words, by placing the resonant frequency of the aforementioned vibratory system at the higher range, the frequency deterioration normally inherent in such systems is boosted so that the overall characteristic of reproduction may be

virtually uniform over a far greater frequency range than heretofore practicable. I have found that a mechanical reproducer constructed in accordance with the invention has uniform or substantially flat frequency response characteristics up to 10,000 cycles and even higher.

The lower surfaces of casing 33 extend only slightly above the operating point of the stylus structure. In the event that a heavy pressure is exerted upon the device against the top surface of a record, and the head be drawn laterally across the grooves, the danger of injurious scratching of the record is obviated. This is apparent because the lower surfaces of housing 33 limit the movement of the stylus point upwardly with respect to the pole pieces 6 and 7. Therefore the maximum spring force acting upon stylus point 2 by flexure of spring 24 is quite small. The torsional twisting of spring 24 along its longitudinal axis permits the point 2 to ride over the walls of the record grooves in the event that the device is forcibly moved transversely of the record. Stylus point 2 readily rides over the walls of the groove by slanting about the axis of the spring 24. Furthermore, inadvertent dropping of the head on the record will not cause injury to the record or stylus.

It is to be noted in Fig. 6 that adjacent surfaces 19 and 20 of magnetic member 17 and armature 4 slope. This slope is such as to reduce any variation in the air gap between these two surfaces irrespective of the transverse flexure of the spring 24. Spring 24 in Fig. 6 is shown flexed to about its normal extent while the device is in operation.

The manner in which the invention device may be utilized for recording will be understood by those skilled in the art, and will now be summarized. In such instances, the recording impulses are electrically introduced to coil 10. The magnetic flux through core 13 is thereupon caused to vary in accordance with the impulses to be recorded. The magnetomotive force supplied by coil 10 causes the central magnetic portion (including core 13, member 17, and armature 4) to be magnetized with an alternating or pulsating magnetic flux in correspondence with changes in the current fed to coil 10. This magnetic portion reacts magnetically with the pole pieces of the permanent magnet. Armature 4 will thereupon be deflected alternately between pole pieces 6 and 7 as the induced polarity of the armature 4 changes, controlling the action of stylus point 2 in cutting the record pattern.

A modified form of the invention is illustrated in Figs. 8 to 11. Armature 39 in this case is similar to the one already described. It operates in the air gap between pole pieces 40, 41. These pole pieces are formed as extensions of the horizontal legs 42, 43 of shoes 44, 45, made of magnetic material. The vertical legs of shoes 44, 45 are placed in contact with the polar ends 46 and 47 of a permanent horseshoe magnet 48. Torsion spring support 49 has its free end attached to the top of the armature 39. Its other end is preferably attached to a magnetic member 50, as by soldering. It is placed next to the bottom surface of the cylindrical core 51 for coil 52. Here the axis of the coil 52 is transverse to the axis of spring arm 49. Magnetic member 50 serves the same function as magnetic member 17 of the form first described. Torsion spring 49 is held in place by the aid of screw 55 passing through magnet member 50, being threaded into core 51.

A non-magnetic supporting member 53 is utilized to support the structure. Horizontal legs 75

42, 43 of the shoes 44, 45 may be attached to the forward end of supporting member 53, as by the aid of the fastening means 54. This support 53, shown most clearly in Fig. 10, has a central depression 56 through which the bottom of core 51 passes. The supporting member 53 is held in place, as by being clamped between spring member 49 and the bottom of coil 52, or by soldering, welding, or a force fit.

To ensure that magnetic member 50 will not be displaced from the central position illustrated in Fig. 11, member 53 may have inwardly extending projections 57, 58, defining a space beyond which the end of magnetic member 50 passes. These projections restrain magnetic member 50 from lateral movement. Since spring 49 is attached to member 50, these projections thus indirectly serve to center armature 39 in the gap between the pole pieces 40, 41. Furthermore, a cover plate 59 (which may be of either magnetic or non-magnetic material), may extend across the top of the permanent magnet 48, as well as across the top of coil 52. It may be held in place by the aid of screw 60 threaded into the upper end of core 51.

Armature 39 carries, as before, a stylus body 61 having a stylus point 62. The mode of its operation is substantially identical with the mode of operation described in connection with the form illustrated in Fig. 1. The magnetic circuits through core 51 may be traced from north pole piece 40, armature 39, magnetic member 50, core 51, permanent magnet 48, shoe 44, back to the north pole. This magnetic circuit passes an increased magnetic flux upwardly through core 51 whenever armature 39 is tilted toward the north pole. When armature 39 is tilted in the opposite direction a strong magnetic flux passes downwardly through core 51 in the following manner: from the north pole of horseshoe magnet 48, downwardly through core 51, magnetic member 50, armature 39, south pole 41, shoe 45, and back to the permanent magnet.

The sole support for the stylus 61, 62 may be torsion spring 49, as hereinbefore, although additional supports might be used. This torsion spring can twist about its longitudinal axis to comply with the vibration of the stylus, and it can also flex upwardly when the stylus structure is placed in contact with the record.

By appropriate design of the torsion spring it is possible to secure the desired suitable resilience in torsion and flexure in various directions. This may be effected by suitable changes in thickness of the spring, its length, its width, or the taper. Also, for example, it may at times be desirable to provide a channel rib 63 centrally of the torsion spring 64 as illustrated in Figs. 12 and 13. This has the effect of more nearly confining the vertical flexure to the place where the torsion spring 64 is anchored.

Somewhat the same effect may be secured by aid of the construction illustrated in Figs. 14 and 15. Here the torsion spring 65 is shown as having an arched configuration 67 adjacent where it is attached to the armature 66. This arched configuration gradually tapers and becomes shallower as the place of anchorage is approached.

In the form of the supporting torsion spring 68 illustrated in Figs. 16 and 17, the axis of torsion is spaced still further above the axis 69 of the pole pieces. This is accomplished by providing a sloping portion 70 which slopes upwardly from the point of anchorage of the spring 68

toward the armature 71. At the free end of the portion 68 the spring 78 drops downwardly for attachment to the top surface of the armature 71. The axis of oscillation of the vibrating structure may be represented by point 72, illustrated in Fig. 17. The movement of armature 71 in the air gap is made more nearly to correspond with the lateral movement of the stylus point 73. The volume of reproduction is thereby increased, and in recording greater forces are available to act on the record groove.

The forms described above incorporate only a single coil. It is well known that a structure of this type is susceptible to extraneous magnetic fields. In cases where the recorder or pick-up is to be used in locations with strong extraneous magnetic fields, the coil and core structure may take the form of a U-shaped core and double coil in accordance with the hum-bucking principle now extensively used in the construction of transformers. The coils may of course be wound with any electrical impedance desired.

Although I have described and illustrated preferred exemplifications which my invention may assume in practice, it is to be understood that modifications may be made therein without affecting the principle and scope thereof as defined in the appended claims.

What is claimed is:

1. A sound translating device for lateral recording comprising means forming a pair of opposed magnetic poles and a central return path portion, an armature disposed between and having surfaces cooperative with said poles and portion, a stylus carried by said armature, a leaf spring serving as the principal support for said armature and having a torsion axis spaced at a substantial distance from the axis of said poles, the opposed surfaces of said portion and armature being similarly sloped transversely to reduce air gap variations therebetween corresponding to flexures of said spring.

2. In a sound translating device for lateral recording, means forming a pair of spaced magnetic poles of opposite polarity, an armature disposed in the space between the poles, a stylus carried by said armature, coil means, a core for said coil means having one end in the magnetic circuit to both poles, means cooperating with said armature to complete the magnetic circuit through the armature and the core by way of either pole, and means providing for said armature to move pivotally with respect to said poles to reduce the magnetic reluctance for a circuit through one pole and to increase the magnetic reluctance for a circuit through the other pole in correspondence with lateral displacements of said stylus comprising a torsion spring having an axis of torsion spaced a substantial distance from the pole axis and forming the sole support for the armature.

3. A sound translating device for sound recording comprising means forming a pair of spaced magnetic poles of opposite polarity, an armature disposed in the space between the poles, a stylus carried by said armature, coil means, a core for said coil means having one end in the magnetic circuit to both poles, means cooperating with said armature to complete the magnetic circuit

through said armature and said core by way of either pole, and means providing for permitting said armature to move pivotally with respect to said poles to reduce the magnetic reluctance for a circuit through one pole and to increase the magnetic reluctance for a circuit through the other pole in correspondence with lateral displacements of said stylus comprising a torsion spring having an axis of torsion spaced a substantial distance from the pole axis, and forming the principal support for the armature, said spring having freedom of torsional twist as well as in a direction transverse to the spring at the place where the armature is supported.

4. In a sound translating device for lateral recording, means forming a pair of spaced magnetic poles of opposite polarity, an armature disposed in the space between the poles, a stylus carried by said armature, coil means, a core for said coil means having one end in the magnetic circuit to both poles, magnetic means cooperating with said armature to complete the magnetic circuit through said armature and said core by way of either pole, and means providing for said armature to reduce the magnetic reluctance for a circuit through one pole and to increase the magnetic reluctance for a circuit through the other pole in correspondence with lateral displacements of said stylus comprising a torsion spring having an axis of torsion spaced a substantial distance from the pole axis and forming the principal support for the armature, said spring axis being transverse to the pole axis.

5. A sound translating device comprising means forming a pair of spaced magnetic poles of opposite polarity, an armature disposed in the space between said poles, coil means, a core for said coil means having one end in the magnetic circuit to both poles, magnetic means cooperating with said armature to complete the magnetic circuit through said armature and said core by way of either pole, and means providing for said armature to reduce the magnetic reluctance for a circuit through one pole and to increase the magnetic reluctance for a circuit through the other pole comprising a torsion spring having an axis of torsion spaced a substantial distance from the pole axis and forming the principal support for said armature, and supported by the aid of said magnetic means.

6. A sound translating device of the character described comprising means forming a pair of spaced magnetic poles of opposite polarity, an armature disposed in the space between the poles, coil means, a core for said coil means having one end in the magnetic circuit to both poles, a stylus carried by said armature, magnetic means cooperating with said armature to complete the magnetic circuit through said armature and said core by way of either pole, and means providing for said armature to reduce the magnetic reluctance for a circuit through one pole and to increase the magnetic reluctance for a circuit through the other pole comprising a torsion spring having an axis of torsion spaced a substantial distance from the pole axis and forming the sole support for the armature.

HENRY H. BRUDERLIN.
